UNITED STATES PATENT OFFICE.

ERAPHIA A. SWIHART, OF RANDALL, KANSAS.

INCUBATOR.

Application filed May 7, 1921. Serial No. 467,593.

To all whom it may concern:

Be it known that I, ERAPHIA A. SWIHART, a citizen of the United States, residing at Randall, in the county of Jewell and State 5 of Kansas, have invented certain new and useful Improvements in Incubators, of which the following is a specification.

This invention relates to incubators and the main object thereof is to provide an 10 incubator in which the admission of air and the temperature is automatically controlled.

Another object of the invention is to provide an incubator with thermostatically controlled dampers to simultaneously let out 15 the hot air from the incubating chamber, admit fresh air to said chamber and close the heater damper when the temperature in the incubating chamber exceeds a predetermined point.

With these and other objects in view, the 20 invention consists in certain novel features of construction as hereinafter shown and described and then specifically pointed out in the claims.

In the drawings wherein like reference 25 characters denote corresponding parts throughout the several views:

Figure 1 is a top plan view of an incubator in accordance with this invention.

Figure 2 is a sectional plan thereof.

Figure 3 is a central longitudinal vertical section thereof.

Figure 4 is a transverse vertical section thereof.

Figure 5 is an enlarged detail view, in 35 rear elevation, showing the damper for controlling the admission of fresh air to the incubating chamber.

Figure 6 is an enlarged detail section on 40 line 11—11, Figure 1.

Figure 7 is a detail in transverse section through the egg tray showing the protector in use.

The incubator 1 constituting this invention 45 comprises a double walled structure except at the front where the door 2 is mounted and which extends preferably throughout the length of the incubator being shown hinged to open downwardly (see Fig. 4) and 50 comprises an outer protective member and an inner glass member 3, the latter being provided to afford a view of the interior of the incubator without necessitating opening the door, such opening being objectionable because of the change in temperature 55

in the incubating chamber incident thereto.

The incubator herein shown is rectangular in construction and mounted on suitable legs 4, although obviously it may be mounted 60 on any suitable support.

The incubating chamber, which is indicated at 5, has its top provided with a hot air outlet 6, and means mounted in its rear wall to provide a fresh air inlet, and which consists of a substantially T-shaped pipe, 65 comprising a stem 8 and a head 9. The stem 8, projects through a transverse opening 7, in the rear wall of the incubating chamber, and has its outer end open to the atmosphere, and the said outer open end of 70 the stem 8, is controlled by a damper to be hereinafter referred to. The head 9 of the fresh air inlet pipe, is arranged adjacent to the inner face of the rear wall of the incubating chamber 5, and which is disposed 75 longitudinally in relation thereto, and said head 9 is provided with a plurality of perforations 9^a, formed in the front thereof to discharge the fresh air in a plane above the egg tray (see Fig. 3).

The heating system for the incubating chamber comprises an upright pipe 10, mounted outside the chamber 5, at one end of the incubator into which extends a heater 11, here shown in the form of a lamp mounted on a suitable bracket carried by the incubator frame. This upright pipe 10, is carried by a tubular casing 12, with the interior of which the pipe 10 communicates, as is shown in Fig. 3. This casing 12, is 80 made in the form of a double walled structure and the space between the walls thereof constituting a water chamber 13, from which lead two pipes 14 and 15, the upper one 14 of which after entering the incubating 85 chamber 5, is bifurcated and the members 16 and 17, thereof extend in opposite directions around the sides and ends of the incubating chamber above the egg tray presently to be described. At the end of the 90 chamber 5, opposite to that end through which the pipes 14 and 15 enter, the pipe sections 16 and 17 communicate with the return pipe 15 (see Fig. 2). These pipes in connection with the water chamber 13, form 95 a water circulating system for supplying hot water to the incubator chamber and thereby providing sufficient heat for the incubation of the eggs.

As shown in Fig. 2 two baffle plates or 110

deflectors 18 and 19, are arranged one at the point where the inlet pipe 14, communicates with the pipe sections 16 and 17, and the other at the point where these pipes communicate with the return pipe 15. These deflectors or baffle plates are made V-shaped in cross section with the apices thereof extending toward the pipes 14, and 15 respectively. The baffle 18, operates to divide and 10 direct the water entering through pipe 14 into the branch pipes 16 and 17, while the baffle 19, directs the return water into pipe 15 from the branch pipes 16 and 17.

Means for supplying water to the system 15 is shown in the form of a funnel 20, opening through the top wall of the pipe 14, adjacent the connection thereof with the chamber 13.

The casing 12, is provided with a plurality of longitudinally extending radiating spacing plates 21, to hold the casing 12, spaced from an outer shell 22, composed of two sections 23 and 24, closed at their outer ends as shown at 25, said sections when 25 combined being longer than the casing 12, and into which said casing opens at its opposite ends as shown in Figure 9, the heated air which enters the casing 12, through pipe 10, passing out of the ends of said casing 30 into the shell 22, and out around the inner ends of the sections thereof which are open to the atmosphere.

The pipes 14 and 15 and the branches 16 and 17 thereof, are made flat being preferably rectangular in cross section as shown 35 in Figs. 4 and 5, and by so forming them a more uniform heat will be radiated therefrom onto the eggs in the egg tray of the incubating chamber.

A thermostat 26, is supported in the incubating chamber 5, above the egg tray thereof and a threaded rod 27, rests at one end on said thermostat and extends loosely through the top wall of the incubator as shown 40 clearly in Fig. 6, the opening through which said rod 27, passes being preferably surrounded with a pipe as shown at 28, which permits the free movement of the rod 27, and prevents heated air in the incubating 45 chamber from passing out into the space between the walls of the incubator. This threaded rod 27, passes upwardly and has threaded engagement with a block 29, carried by a lever 30, which lever is fulcrumed 50 on an upstanding post 31, carried by the incubator top as is shown clearly in Fig. 11. This rod 27, is provided at its upper end with a knurled head 27a, to facilitate its adjustment in the block 29, it being obvious 55 that this is necessary to properly adjust the lever 30, for indicating the temperature within the incubating chamber 5, said lever cooperating with a scale 32, mounted on the incubator top as shown clearly in Figs. 4 60 and 6. This scale 32, is slidably mounted

in suitable guides 33, and has a laterally extending arm 34, on its rear face with which a rod 35, has threaded engagement. This threaded rod 35, passes loosely through another arm 36, which connects the slide members 33, and the lower end of said rod has swivelled connection with a plate 37, mounted on the incubator top and which also carries the post 31, on which the lever 30 is fulcrumed.

A substantially U-shaped rod has the legs or arms thereof adjacent its cross bar 39, mounted for vertical movement in two brackets 40, carried by the top of the incubator as shown clearly in Fig. 1. The arm 41 of actuating rod carries at its free end a damper 42, which is positioned over the outlet opening 6, of the incubating chamber 5, and is employed for controlling said opening to regulate the passage of the heated air from the incubator.

The arm 43 of the actuating rod is deflected laterally adjacent the bracket 40, in which it is pivotally mounted, and said arm extends outwardly over the heating tank 22, and carries at its free end a damper 44, which is located directly over the vertical pipe 10, of the heater and controls the amount of heated air permitted to pass outwardly through the upper end of the pipe 10.

The damper actuating rod is so mounted and balanced on the brackets 40, that the dampers 42 and 44 will be simultaneously raised and lowered on the rocking of said rod in the brackets 40.

The cross bar 39 is offset intermediate its ends, as at 45, and engaging with said offset 45 is the outer end of the lever 30, which is controlled by the thermostat 26 in the incubating chamber 5.

Mounted on the rear edge of the top of the incubator is a vertically disposed plate 46, provided with longitudinally extending V-shaped notches 47, in its upper edge and with which rockingly engage the ends 48, of a U-shaped member 49, carried by the upper arm of an L-shaped shifting rod. The ends 48, of the member 49, are provided with V-shaped notches and which engage in the V-shaped notches 47, of the plate 46.

The L-shaped shifting rod includes an upper arm 51 and a lower arm 52, the former being shorter than the latter, and said arm 51 extends horizontally and has its free end positioned under the cross bar 39, of the actuating rod, as shown in Fig. 1. The long arm 52 of the rod shifting depends parallel with the rear wall of the incubator and carries at its free end a damper 53, which is positioned opposite the open end of the stem 8, of the air inlet pipe, as is shown clearly in Fig. 11. The shifting rod is so balanced and connected in relation to the lever 30, that when the parts are in normal position, as shown in Fig. 11, with

the temperature in the incubating chamber 5 standing at 103, the damper 53, will be positioned slightly away from the stem 8, of the inlet pipe to permit sufficient air to enter the incubating chamber, to sustain the proper temperature within the cylinder and to supply the required oxygen thereto. The dampers 42 and 44 carried by the actuating rod will also be positioned, as shown in Fig. 2, so that the proper amount of hot air will be permitted to pass out from the incubating chamber and also from the pipe 10.

The damper 53, is provided with an opening 54, so that when said damper is closed the proper amount of air will be permitted to pass into the incubating chamber through said opening.

Mounted to slide in and out of the incubating chamber 5, is an egg tray 55, supported by tracks in the form of vertically spaced cleats 56, and which is designed to be inserted and removed through the door at the front of the incubator. This incubator tray 55, is open at its top and bottom and has mounted in the side members thereof a plurality of rotatable egg supporting rollers 57, any desired number of which may be employed according to the size of the tray provided that they be positioned sufficiently close to support the eggs and prevent them from dropping between the rollers. These rollers 57, are made of wood or other suitable non-conducting material. These rollers 57, are provided at each end with journals 58 and 59, having bearings in the side members of the tray, the journals 59 extending through the side member in which they are mounted and each is provided at its projecting end with a link or crank 60. These links or cranks 60, are of uniform length and are connected at their other ends by an actuating bar 61, which when moved in one direction operates through the links 60 to turn the rollers 57, and incidently to turn the eggs which are carried by the rollers. It will thus be seen that all of the eggs mounted on the rollers 57, as shown in Fig. 3, may be simultaneously turned by manipulating the bar 61, in the manner above set forth without moving the tray thereby avoiding unnecessary handling of the eggs and the jars incident to the removal and insertion of the tray.

A drain cock 62, is located at the bottom of the water chamber 13, and is designed for draining the water from the system when not in use.

In the use of this incubator the tray having been filled with eggs and placed in the incubating chamber 5, and the doors thereof closed, the lamp 11 is lit, after the lever 30, has been properly adjusted to set the free end thereof in relation to the scale 32, to show the temperature in the incubating

chamber 5, which is to be maintained, it of course being understood that the water system has first been filled and the incubator is then ready for use and will automatically operate without any further attention by the attendant, except when it is necessary to turn the eggs which are manipulated in the manner above described by actuating the bar 61.

Should the heat in the incubating chamber 5, rise beyond the desired temperature to be maintained, the thermostat 26, will expand thereby rocking the lever 30, lowering the end thereof which is engaged with the cross bar 39 of the actuating rod. This lowering of the lever end operates through said actuating rod to raise the dampers 42 and 44 and through the shifting rod to open damper 53, thus permitting the hot air in the incubating chamber to pass out through the outlet and the fresh air to rush in through the inlet pipe. Simultaneously the raising of the damper 44, permits the hot air from the heater to pass out through the upper end of the pipe 10. When the damper 44 is raised sufficiently to permit all of the hot air to be drawn out a vacuum will be produced and operate to draw in cold air through the pipe 10, thereby effecting a cooling instead of a heating action on the water in the chamber 13, and preventing all possibility of the eggs of the incubating chamber being overheated.

A few days before the hatch is due, that is on about the 18th day, the eggs are lifted out of the tray and a cloth 63, placed over the rollers 57, and the eggs again replaced on the said cloth. This cloth by completely covering the rollers at the bottom of the tray will operate to protect the chicks which hatch from contact with the rollers and also prevent the egg shells and other refuse from coming in contact with the rollers 57, so that these are maintained in clean condition and after the hatch is completed the cloth 63, is removed taking out the shells and all other refuse leaving the tray ready to be refilled without any additional cleaning.

By constructing the heater as above set forth it will be obvious that it may be readily disassembled for cleaning or repair even during a hatch if need be since very little time will be taken for separating the various parts and connecting them up.

The preferred embodiment of the invention is disclosed in the drawings and set forth in the specification, but it will be understood that any modifications within the scope of the claimed invention may be made in the construction without departing from the principle of the invention or sacrificing any of its advantages.

What I claim is:

1. An incubator comprising a body portion providing an incubating chamber hav-

- ing a hot air outlet, a fresh air inlet and a heating means, a thermostat arranged therein and including a vertically disposed stem projecting through the top of said body portion, a U-shaped actuating rod mounted on said body portion and provided at its free end with synchronously operable dampers for controlling said outlet and heating means, a shifting rod pivoted on and depending from said body portion and having a damper for controlling said inlet and further controlled by the operation of said actuating rod, and a lever pivotally supported on said body portion and connected with the stem of said thermostat for actuating said actuating rod causing thereby the shifting of the dampers carried by said rod and the shifting of the damper carried by said shifting rod.
2. In an incubator, an incubating chamber, a thermostat arranged in said chamber and having a stem extending through the top wall thereof, a U-shaped actuating rod having its legs mounted for rocking movement adjacent the connecting cross bar for said legs, one of said legs being extended outwardly at an oblique angle and provided at its free end with a damper for controlling, a heat supply device, said chamber having an air outlet, a damper at the free end of the other leg of said member for controlling said air outlet, and a lever connected with said thermostat stem and with said connecting cross bar to rock said rod and open said dampers.
3. In an incubator, an incubating chamber having a fresh air inlet in one end wall thereof, a thermostat arranged in said chamber and having a stem extending through

the top wall thereof, an L-shaped shifting rod having a U-shaped member secured to one arm thereof and extending on opposite sides of said arm, said U-shaped member being rockingly supported on said chamber, the other arm of said rod extending opposing that end of the chamber having the inlet and provided with a damper for controlling said inlet, and means engaging with that arm of said rod provided with the U-shaped member and operable by the thermostat for actuating said rod to open said damper when the heat in the chamber exceeds a predetermined limit.

4. In an incubator, a body portion providing an incubating chamber, a thermostat arranged within said chamber and including a vertically disposed stem projecting through the top of the body portion, means to provide said chamber with an air inlet, a hot air outlet and a heating means, a U-shaped actuating rod mounted on said body portion and provided at its free ends with synchronously operable dampers for controlling said outlet and heating means, an L-shaped shifting rod pivotally mounted on and depending from said body portion and provided with a damper for controlling said inlet, said shifting rod controlled by the operation of said actuating rod, and a lever pivotally supported on said body portion and connected with said stem for rocking said actuating rod causing thereby the shifting of the dampers carried by the actuating and shifting rods.

In testimony whereof I affix my signature 75
hereto.

ERAPHIA A. SWIHART.
